UNITED STATES PATENT OFFICE.

WILLIAM M. IRICK, OF SAN ANGELO, TEXAS, ASSIGNOR OF ONE-HALF TO JAMES B. GANONG, OF SAN ANGELO, TEXAS.

POCKET-KNIFE.

1,012,555.

Specification of Letters Patent.

Patented Dec. 19, 1911.

Application filed April 12, 1911. Serial No. 620,639.

To all whom it may concern:

Be it known that I, WILLIAM M. IRICK, a citizen of the United States, and a resident of San Angelo, in the county of Tom Green and State of Texas, have invented a new and Improved Pocket-Knife, of which the following is a full, clear, and exact description.

My invention relates generally to pocket knives and more particularly involves one 10 having the handle portion thereof provided with a suitable sharpening device.

The object of my invention is to provide a pocket knife having a whet stone or other suitable sharpening material provided in one 15 side of the handle thereof, this handle portion being removably secured to the bolsters of the knife, together with convenient means permitting the removal of the handle portion when it is desired to use the stone or 20 sharpening material.

While I have shown my invention applied to a pocket knife, it is obvious that it may be applied to the handle portion of any 25 knife, such as a butcher knife or a hunting knife.

Reference is to be had to the accompanying drawings forming a part of this specification, in which like characters of reference denote corresponding parts in all the 30 views, and in which—

Figure 1 is a side view of a pocket knife embodying my invention; Fig. 2 is a horizontal sectional view thereof, on the line 2—2 of Fig. 1; Fig. 3 is a side view of the 35 knife showing the handle portion removed; Fig. 4 is a side view of the detached handle portion showing the sharpening material; Fig. 5 is a vertical sectional view, on the line 5—5 of Fig. 2.

40 The handle portion of my knife is provided with the usual scale pieces 1, 2, together with bolsters 3, 4, each pair of bolsters being suitably held together by means of rivets 5, 6, each rivet forming a bearing 45 for a blade 7, 8. Each scale piece 1, 2, is removable and the inner portion thereof is provided with a whet stone or a piece of carborundum 9 which is suitably held in position thereon. The inside face of each 50 of the scale pieces is provided with a longitudinally extending portion 10 having normally projecting parts 11, 12, at opposite

ends thereof, which projecting ends, together with the portion 10, constitute a pocket. The portions 10 at one end of each 55 scale piece are extended whereby a member 14 results which is adapted to be received in a recess 15 contained in each of the bolsters 3 and adjacent the lower portion thereof. Each of the scale pieces is suitably secured to the portions 10 by means of rivets 16, 17. Each scale piece adjacent one of its ends and at its inner side portion is provided with a longitudinally extending slotted portion 18, each portion communicating with a recess adjacent the outer face of the scale piece, which recess is adapted to have a suitable bearing member 19 placed therein, which member is provided with an opening 20 within which the pin 21 is movable. In each of the recesses 18 a catch 22 is seated, one end of the catch being engaged in a suitable recess 23 contained in the bolster 4. The pin 21 is provided with a suitable gripping portion 25, the upper 75 edge of which is wholly included within the bearing member 19 whereby no projecting parts result, the end 25 being freely movable back and forth within this bearing member. The material 9 which forms the whet stone 80 or other sharpening element is brought into position for use by sliding the pin 21 (as shown in Fig. 2) to the left, thereby carrying the catch 22 out of engagement with the bolster 4 when the scale piece may be easily 85 lifted out, the recess 15 in the opposite bolster 3 being conveniently shaped to permit the extending part 11 to be freely withdrawn.

While I have shown my invention in a 90 single embodiment, it is obvious that many changes may be made in the construction thereof without departing from the spirit of the invention as defined in the appended claims.

95 Having thus described my invention, I claim as new, and desire to secure by Letters Patent:—

1. A pocket knife having the scale piece thereof provided with a longitudinally extending member on its inner face, projecting parts adjacent the ends of the said longitudinally extending member whereby a pocket is formed, a suitable sharpening

material contained in the said pocket, one end of the said longitudinally extending member being provided with an extended portion, a recess in the inner portion of the 5 said scale piece, and adjacent the opposite end of the said longitudinally extending member, a movable member contained in the said recess and having a transversely extending gripping portion at one end thereof 10 passing through the said scale piece, the bolsters of the knife being provided with recesses receiving the said extended portion and one end of the said movable member, whereby the said scale piece with the sharpening material thereon is suitably held in 15 position.

2. A pocket knife having the scale piece thereof provided with a longitudinally extending member on its inner face, projecting 20 parts adjacent the ends of the said member whereby a pocket is formed, a suitable sharpening material contained in the said pocket, one end of the said longitudinally extending member being provided 25 with an extended portion, a recess in the inner portion of the said scale piece and adjacent the opposite end of the said longitudinally extending member, a recess adjacent the outer face of the said scale piece, a 30 movable member contained in the first said recess, a pin carried by the said movable member having at its outer end a gripping portion movable in the recess in the outer face of the said scale piece, the bolsters of 35 the knife at opposite ends thereof being provided with recesses receiving the said extended portion and one end of the said movable member, whereby the said scale piece with the sharpening material thereon is 40 held in position.

3. A pocket knife having the scale piece thereof provided with a longitudinally extending member on its inner face, projecting parts adjacent the ends of the said 45 longitudinally extending member whereby a pocket is formed, means for holding the said member on the said scale piece, one end of the longitudinally extending member being provided with an extended portion, a 50 recess in the inner portion of the said scale piece and adjacent the opposite end of the said longitudinally extending member, a catch contained in the said recess, one end of the catch being provided with a pin and 55 the pin being provided with a gripping portion, a recess in the outer face of the said scale piece into which the said pin and gripping portion extend, the said catch being movable within the first recess and the said 60 gripping portion being movable within the second recess, the opposite bolsters of the knife being provided with recesses, one of which is adapted to receive the said extended portion, and the other adapted to re-

ceive one end of the said movable member, 65 whereby the said scale and the sharpening material thereon is held in position.

4. A pocket knife having the scale piece thereof provided with a longitudinally extending member on its inner face, projecting parts adjacent the ends of the said longitudinally extending member whereby a pocket is formed, means for holding the said longitudinally extending member on the said scale piece, a suitable sharpening material contained in the said pocket, one end of the longitudinally extending member being provided with an extended portion, a recess in the inner portion of the said scale piece and adjacent the 80 opposite end of the said longitudinally extending member, a recess in the outer portion of the said scale piece and communicating with the first-mentioned recess, a catch contained in the first-mentioned recess and movable therein, the said catch being provided with a pin and a gripping portion movable within the said second recess, the said gripping member being wholly included within the said recess whereby no 90 projecting portions result, the opposite bolsters of the knife being provided with recesses, one of the said recesses adapted to receive the said extended portion and the other recess adapted to receive one end of the said catch, the said catch being movable in order to carry it out of engagement with the said recesses whereby the scale piece with the sharpening material thereon may be brought out of engagement with the said 100 bolsters, thereby making the sharpening material available.

5. A pocket knife comprising a scale piece and bolsters, one of the bolsters being provided with an opening, the scale piece being provided with a pocket on its inner face, sharpening material contained within the said pocket, a projecting part at one end of the said scale piece and adjacent the inner face thereof and adapted to engage one 110 of the bolsters, a longitudinally extending recess in the inner portion of the said scale piece and adjacent the opposite end thereof, another recess in the outer portion of the said scale piece and communicating with the said longitudinally extending recess, a longitudinally extending member positioned within the said inner recess and movable therein, the outer end portion thereof being adapted to engage in the opening in the said 115 bolster, the opposite end of the said member being provided with a transversely extending pin projecting into the recess in the outer portion of the scale piece, a gripping portion at the outer end of the said pin, the said gripping portion being positioned within the said recess in the scale piece 120 whereby movement of the gripping portion

will move the said member within the said recess whereby the end of the said member may be brought out of engagement in the recess in the bolster whereby the scale piece and the sharpening material thereon may be removed from the said knife.

5 In testimony whereof I have signed my

name to this specification in the presence of two subscribing witnesses.

WILLIAM M. IRICK.
